UNITED STATES PATENT OFFICE.

WALTER S. DALEY, OF LOS ANGELES, CALIFORNIA, ASSIGNOR OF ONE-HALF TO DAVID S. WILLIAMS, OF LOS ANGELES, CALIFORNIA.

JOURNAL-BOX LUBRICATOR.

1,285,060.

Specification of Letters Patent. Patented Nov. 19, 1918.

Application filed December 28, 1917. Serial No. 209,285.

To all whom it may concern:

Be it known that I, WALTER S. DALEY, a citizen of the United States, residing at Los Angeles, in the county of Los Angeles and State of California, have invented a new and useful Journal-Box Lubricator, of which the following is a specification.

This invention relates to a journal-box lubricator and particularly pertains to a mechanism for delivering lubricant to the journal or bearings of wheels such as are employed on rail-way trains, street cars and the like.

It is the object of this invention to provide means for mechanically lubricating journals whereby the use of waste may be dispensed with; the invention primarily residing in a pan serving as a lubricant reservoir adapted to be inserted in a journal-box and mechanism carried by the pan for feeding the lubricant to the journal.

A further object is to provide means on the pan for packing the heel of the journal to prevent dirt and foreign substances from entering the reservoir through the back wall of the journal-box.

Other objects will appear hereinafter.

The invention is illustrated in the accompanying drawings, in which:

Figure 1 is a view in longitudinal vertical section of a journal-box showing the invention as applied.

Fig. 2 is a view of same in cross section.

Fig. 3 is a plan view of the lubricant feed roller.

Fig. 4 is a detail of the journal packing.

More specifically 6 indicates a journal-box of ordinary construction having a rear wall 7 formed with an opening 8 through which the wheel spindle or journal 9 extends; the journal being formed with a reduced portion 10 which seats on its upper half in the usual bushing 11.

In carrying out my invention I employ a pan 12 shaped to conform to the bottom and side portions of the journal-box which pan serves as a container for the lubricant and is formed of sheet metal not easily fractured so as to hold the lubricant in event the journal-box is cracked. This pan is formed with a rear wall 13 extending transversely across the journal-box and having an arcuate cut-

away portion to extend approximately around the lower half of the journal. Carried on the edge of the arcuate portion of the rear wall is a packing segment 14 formed of felt or similar material here shown as split on its outer edge and positioned astride of the end wall. This packing contacts the journal and encircles the lower half thereof with its ends abutting against the bushing 60 so as to effectively close communication between the open rear end of the journal-box and the interior of the pan and thereby prevent ingress of dirt and foreign substances.

Mounted in the pan is a standard 15 on which a rocker arm 16 is pivoted; this arm being formed with a yoke 17 on its inner end in which a lubricant distributing roller 18 is revolvably mounted. The outer end of the arm 16 is formed with a weight 19 for normally maintaining the roller in contact with the journal.

In the operation of the invention a lubricant is placed in the pan to a sufficient depth to partly submerge the roller 18, which roller will be positioned in contact with the journal by action of the weight 19. On rotation of the journal the roller 18 will revolve and carry the lubricant adhering to its circumferential surface to the journal.

By the use of this invention the employment of cotton waste or the like may be dispensed with and by providing the separate lubricant pan loss of the lubricant will be avoided in event of fracture of the journal-box.

I claim:

1. The combination of a journal box, a journal therein, a pan insertible in the box beneath the journal having a vertical rear wall formed with an arcuate edge encircling the lower half of the journal, a packing strip on said edge contacting the journal and the inner face of the rear wall of the pan, and mechanism carried by the pan for delivering lubricant from the pan to the journal as the latter revolves.

2. A journal lubricator comprising in combination a journal box, a journal extending therein, a pan adapted to be removably disposed in a journal box, means on the pan for packing the lower half portion of the joint

between the journal and pan, and mechanical means carried by the pan for delivering lubricant from the pan to the journal as the latter revolves.

5. 3. In a journal lubricator, the combination of a journal-box, a journal therein, a pan carried in the journal box having a rear

wall encircling the lower half of the journal, a packing segment on said wall contacting the journal, a lubricant feed roller carried by the pan, and a weight normally maintaining said roller in contact with the journal.

WALTER S. DALEY.
